UNITED STATES PATENT OFFICE.

JOSEPH H. COOPER, OF PAOLA, KANSAS, ASSIGNOR TO DEARBORN DRUG & CHEMICAL WORKS, OF CHICAGO, ILLINOIS, A CORPORATION OF ILLINOIS.

CHEMICAL-FEEDER.

1,075,022.

Specification of Letters Patent.

Patented Oct. 7, 1913.

Application filed July 8, 1912. Serial No. 708,145.

To all whom it may concern:

Be it known that I, JOSEPH H. COOPER, a citizen of the United States, residing at Paola, in the county of Miami and State of Kansas, have invented a certain new and useful Improvement in Chemical Feeders, of which the following is a full, clear, concise, and exact description, reference being had to the accompanying drawings, forming a part of this specification.

My invention relates to systems and apparatus for chemically treating boiler feed water.

While my invention is capable of wider application, it is particularly useful in connection with railway locomotives and injectors which are commonly employed to deliver boiler feed water from the engine tender to the boiler. Ordinarily, there are two injectors mounted upon a locomotive, one upon the fireman's side and the other upon the engineer's side. In accordance with my invention, I provide a single tank or reservoir containing boiler compound or chemical in liquid form. This storage tank or reservoir may be located at any convenient point upon the locomotive. The arrangement and operation of my system is such that the control of the injectors by the engineer and fireman will operate automatically to control the supply of compound or chemical in proportions predetermined in accordance with an analysis of the water fed to the boiler. The chemical supply pipes are connected with the suction pipes or chambers of the two injectors. Each of the chemical supply pipes is provided with a check valve, whereby the operation of either injector will effect the proper operation of the chemical feeding apparatus without interference from the other injector and the connections thereto. The chemical supply pipes are provided with shut-off valves and sight feeders. The pipes leading to the two injectors are combined and led through a single tube to a point near the top of the chemical supply tank. The result is that a suction upon the chemical feed pipe system is necessary to raise the chemical solution from the storage tank. When, therefore, the injectors are not in operation, the supply of chemical automatically ceases. When, however, either injector is put in operation, the suction created in the chemical supply pipe raises the chemical solution from the bottom of the

storage tank to supply chemical in proper proportion as determined by the setting of the chemical regulating valve. This valve is of novel construction and function and is arranged to prevent incrustation and faulty and irregular operation resulting therefrom. The regulating valve is at the bottom of the induction tube of the chemical supply tank, whereby it is kept always in the chemical solution. This alone would go far in preventing incrustation of the valve, but in addition to this I mount the valve at the end of a very long slender stem, preferably of steel. The inevitable vibration of the rod, at the end of which the valve is mounted, causes a movement of the valve which also will prevent an accumulation of sediment.

These and the other features of my invention will be more fully understood by reference to the accompanying drawings, in which—

Figure 1 is a side elevational view of a locomotive equipped with a feed water and chemical injecting apparatus embodying my invention, a portion of the cab being broken away to more clearly reveal the apparatus; Fig. 2 is an end elevational view of a locomotive boiler showing how the water treating and feeding apparatus is positioned; and Fig. 3 is a longitudinal cross-sectional view of the chemical tank taken on the line 3-3 of Fig. 2 and looking in the direction indicated by the arrows.

Similar numerals refer to similar parts throughout the several views.

Referring to the drawings, a locomotive boiler is shown at 4 and a tender at 5 provided with a suitable water tank or reservoir 6. The boiler is provided with injectors 7 and 8 arranged respectively on the right and left hand sides of the boiler. The injectors should be located above the normal water level in the tank 6. The water level is indicated by the line 9.

The preferred construction of the injectors 7 and 8 is shown and described in detail in my co-pending application Serial No. 614,198.

The suction connections of the injectors 7 and 8 are connected with the water tank or reservoir 6 by means of pipes 10 and 11 respectively. The injectors may, if desired, be provided with valves 7' and 8' to close the passages from the water tank to the injectors. The steam supply connections 12

and 13 of the injectors 7 and 8 are connected with pipes 14 and 15. These pipes 14 and 15 are combined and lead to the boiler 4 by means of a suitable T-connection 16. The manual valve 17 is provided to admit steam to the pipes 14 and 15 and thence to the steam connections 12 and 13 of the injectors 7 and 8 respectively.

At 18 is shown the tank which contains the water treating material or chemical. This tank is provided with gage 19 and air vent 20. A pipe 21 is provided through which water treating material or chemical may be admitted to the tank. This pipe 15 may be provided with a manual valve 22 if desired. The tank 18 is provided with an induction tube 18', which in turn is provided with a valve 23 which will be herein-after referred to in detail. Connected with the pipe 24 by means of a suitable coupling, not shown, are the water treating material supply pipes 25 and 26. These pipes lead to the sight feed chambers 27, 28 respectively. Needle valve 29 is provided to regulate the flow of water treating material through the sight feed chamber 27. A needle valve 30 in a like manner regulates the flow of water treating material through the sight feed chamber 28. Leading from the sight feed chambers to the suction chambers of the injectors 7 and 8 are the pipes 31 and 32. Interposed in these pipes are the check valves 33 and 34. These valves are normally held open by gravity and close against an upper seat. Consequently the suction action of each of the injectors 7 and 8 closes the check valve in the feed pipe leading to the other injector. The injectors are provided with the operating levers 35 and 36 as shown.

The operation of the system is as follows: Should the valve 7' be open and it be desirable to inject treated feed water into the boiler by means of injector 7, the operating lever 35 is operated, whereupon a suction is created in the water supply pipe 10 and the water rises up into the injector. At the same time, the pressure in pipe 33 being reduced, water treating material is drawn through valve 23, induction pipe 18', pipes 24 and 25, and valves 29 and 33 into the injector 7. The water treating material and the feed water are then injected into the boiler through a suitable delivery pipe. At the time the water treating material is drawn from tank 18, the check valve 34 is closed, thereby preventing the flow of water treating material to the injector 8. If both injectors should be open at the same time, of course, water treating material would flow to both injectors. If only one injector is in use, as for example the injector at the right-hand side, it may be found desirable to fully close the sight feed valve 30. If the injector on the left-hand side alone is to be

used, the sight feed valve 29 may be closed. Since the regulation of the flow of chemical is controlled by the special valve 23, it is usually preferable to open fully the sight feed valve associated with one or both injectors in conformity with the use of one or both of these injectors.

Referring now to Fig. 3, it will be seen that the induction tube 18' extends down to the tank 18 to almost the bottom thereof. To close the end of this tube the regulating valve 23 is provided. This valve is covered with liquid when the tank is filled with the water treating material. The valve is mounted upon a long slender rod 23'. The vibration of this rod prevents the valve 23 from being incrusted with lime or other sediment from the water treating material. A hand wheel 23" may be provided to regulate the valve 23.

It is apparent that the amount of water treating material which passes to the injectors may be nicely regulated by means of valve 23 and needle valves 29 and 30.

While I have shown my invention in the particular embodiments herein shown and described, I do not, however, limit myself to these constructions, but wish to employ other equivalents which might suggest themselves to those skilled in the art.

What I claim is:

1. In combination, a pair of water feeding devices, each of said water feeding devices having a suction end and a delivery end, a chemical tank, pipes connecting the suction ends of the water feeding devices with the chemical tank, and a check valve in each of said pipes arranged to be held closed when the water feeding device associated with the other pipe is in operation, the check valve in each of said pipes being held closed by the vacuum produced by the water feeding means associated with the other pipe, substantially as described.

2. In combination, a pair of injectors, a chemical tank, pipes connecting each of said injectors with said chemical tank, and a normally open check valve in each of said pipes adapted to close when the injector associated with the other pipe is in operation, the check valve in each of said pipes being closed by the vacuum produced by the injector associated with the other pipe, substantially as described.

3. In combination, a chemical tank, water-feeding means for a boiler, a pipe between said tank and said water-feeding means, said pipe communicating with an induction tube entering said tank at a point above the surface of the liquid therein and terminating below the surface of the liquid therein, said induction tube being provided with a valve at its submerged end, said valve being mounted upon one end of a slender rod extending longitudinally of the induction tube

and being free to vibrate upon said rod to prevent incrustation of said valve, and means carried by the other end of said rod for regulating said valve, all substantially 5 as described.

4. A chemical tank for a feed water treating system comprising a casing, an induction tube carried by said casing entering the same at a point above the normal liquid 10 level therein and terminating below the normal liquid level, said induction tube being provided with a valve at its submerged end to regulate the passage of chemical therethrough, said valve being mounted upon the 15 end of a slender rod extending longitudinally of the induction tube and so being adapted to vibrate to prevent the accumulation of sediment, said valve being beveled at the top thereof, substantially as described.

5. In combination, a pair of injectors, a 20 chemical tank provided with an induction tube entering said chemical tank at a point above the normal liquid level therein and terminating below the normal liquid level, said induction tube provided with a T- 25 connection, and pipes connecting the suction ends of the injectors with said T-connection, the flow of chemical to said injectors being controlled by the vacuum produced in the respective injectors, substantially as de- 30 scribed.

In witness whereof, I hereunto subscribe my name this 27th day of June, A. D., 1912.

JOSEPH H. COOPER.
